UNITED STATES PATENT OFFICE.

WILLIAM ELLWOOD, OF HEMPSTEAD, NEW YORK, ASSIGNOR TO NICHOLAS POWER COMPANY, INC., OF NEW YORK, N. Y., A CORPORATION OF DELAWARE

ADJUSTABLE SHUTTER.

Application filed April 26, 1921. Serial No. 464,592.

To all whom it may concern:

Be it known that I, WILLIAM ELLWOOD, a citizen of the United States, residing at Hempstead, in the county of Nassau, State of New York, have invented certain new and useful Improvements in Adjustable Shutters; and I do hereby declare the following to be a full, clear, and exact description of the invention, such as will enable others skilled in the art to which it appertains to make and use the same.

This invention relates to shutter adjusting devices for motion picture machines, and has for its object primarily to provide an attachment which may be applied to certain types of machines now on the market without change in construction of the machine, and without the use of special tools other than those ordinarily found in the kit of a moving picture machine operator.

A further object of the invention is to provide a device of this character which is of simple and easy operation and of low manufacturing cost, so that it may be readily sold as an accessory to users of motion picture machines.

In the accompanying drawings I have illustrated a preferred embodiment of my shutter adjusting attachment applied to a well known type of machine, known to the trade as Power's cameragraph and described in U. S. Letters Patent No. 1,184,126, issued to Nicholas Power on May 23, 1916, and it is for use in conjunction with this type of machine that my improvement is particularly adapted.

In said drawings,

Figure 1 is a side elevation of the machine showing the shutter support and driving gears therefor with my adjusting device applied thereto;

Fig. 2 is a similar elevation of the other side of the machine showing the adjusting device in greater detail;

Fig. 3 is an elevational view of a modified form of my adjusting device;

Fig. 4 is a plan view; and

Fig. 5 is a horizontal sectional view taken on line 5—5 of Fig. 4.

Referring to the drawings, 1 indicates the frame of the machine which is supplied with the usual film-feeding devices, not shown, but supported with their driving gears on rotating shafts mounted in the

machine frame, two of which shafts are shown at 2 and 3, respectively, in the drawings. The driving mechanism of the machine also embodies a shutter driving shaft 4 supported for continuous rotation in the machine frame and driving the shutter supporting shaft 5 through a spiral gear 6 and spiral pinion 7. The pinion 7 is attached to the shutter shaft 5 which, in the machine above mentioned, is supported on a bracket 8 attached to the machine frame and projecting beyond the front wall thereof in order to position the shutter in front of the lens tube 9 which supports the projecting lenses.

The shutter is held fast to the shaft by means of a clamping bolt 10 and set screw 11 in the usual manner, the set screw working in a keyway in the shutter shaft so that when the shutter is removed for packing it may be replaced by the operator in correct position to insure the wing of the shutter cutting off the light during the interval of motion of the film.

The above described construction is that of the present commercial machine and the adjustment of the shutter shaft is fixed when the machine is assembled at the factory and can only be altered by disengaging the gear and pinion 6 and 7 and re-engaging their teeth to secure a different timed relation of the shutter.

As is well known, it is desirable to have the shutter blade as narrow as possible consistent with covering the entire movement of the film, in order that as much light as possible may reach the screen. With a new machine the shutter blade need be very little wider than theoretically necessary, as determined by the relation of movement and rest of the film, but in practice it is not possible to avoid some lost motion in the gears, and as the machine wears the lost motion increases, thereby requiring a wider shutter to cover the period of film movement than would be necessary if the shutter were capable of slight adjustment to compensate for the lag resulting from the lost motion.

Devices have heretofore been proposed for securing the proper adjustment of the shutter with respect to its shaft while the machine is in operation, but all such devices of which I am aware must either be built into the machine or are too bulky and com-

plicated to make their use altogether desirable.

The object of my present invention has been, therefore, to provide a shutter adjusting device which is readily attached to existing machines and which avoids complicated and cumbersome parts of prior structures.

My improved attachment comprises primarily an adjusting screw 12 having a 10 knurled head to facilitate its rotation and a screw threaded part 13 which is threaded through a collar 14 designed to be attached to the inner face of the supporting bracket 8. The collar 14 is simply a screw eye having 15 its ring threaded to fit the thread 13 and a shank screwed into a hole tapped in the rear face of the bracket, this construction being employed to permit the slight angular movement of the screw resulting from 20 the movement of the bell crank lever 15 through which the shutter shaft is adjusted.

The bell crank 15 is attached to the bracket by means of a pivot screw 16 screwed in a hole tapped in the face of the 25 bracket and at its upper end is provided with a pin 17 engaging a grooved collar 18 attached to the shutter shaft in the open space of the bracket between the pinion 7 and the outer shaft bearing. The horizontal arm of the bell crank lever is connected to the lower end of the adjusting 30 screw 12. In the drawing this connection is shown as consisting of a sleeve 19 slipped over the reduced end of the screw 12 below 35 its threaded portion and serving as an abutment for a collar or screw eye 20 projecting from the side of the arm 15 of the bell crank and adapted to turn slightly in its thread as necessitated by the angular movement of the screw 12. The collar 20 is clamped between the sleeve 19 and the clamping nuts 21 threaded on the end of 40 the screw 12.

The shank of the screw 12 above the 45 threaded portion 13 is long enough to bring the knob into position to be readily turned by the operator. When the knob is turned in one direction or the other the shutter shaft 5 will be adjusted longitudinally in 50 its bearings and as the pinion 7 is fast to the shaft the pinion will be adjusted with relation to its cooperating gear 6 whereby the inter-engaging spiral teeth of the pinion and gear will effect a slight rotary 55 adjustment of the shutter shaft 5 in a direction depending upon the longitudinal adjustment of the shaft effected by the adjusting screw.

By this arrangement, as the machine 60 wears and begins to show a so-called "travel ghost" due to the movement of the film not being completely obscured, the operator may slightly adjust the shutter in the manner described to counteract the lag resulting from the lost motion in the driving

connections and thereby maintain the proper synchronous operation of the film and shutter.

It will be observed that the parts necessary to convert the ordinary non-adjustable shutter into one of the adjustable type are few and are of simple, cheap construction, comprising only the adjusting screw, the bell crank and the collar 18 and their supporting and connecting parts, the spiral gears through which the adjustment is effected being universally employed in machines of this type for insuring a quiet operation of the machine. The attachment of the device to existing machines is very simple, requiring merely the tapping of two small screw holes into the rear face of the shutter bracket 8 which is usually of brass or other soft metal. The actual location of the screw holes in the bracket is not essential, as the collar 18 is held to the shutter shaft by a small set screw which may be positioned at any point along the shutter shaft necessary for proper operation of the adjusting screw. The screw eyes 14 form simple and efficient rocking connections for the adjusting screw 12, the adjustment of which does not require sufficient frequency to necessitate expensive swiveled supports, etc., although of course it is obvious that such supports may be employed in lieu of simple screw eyes, if desired.

In Figs. 3 to 5 I have illustrated a modified form of my adjusting device. The supporting bracket 8^a, in addition to affording a bearing for the shutter shaft 5, is provided with a pair of outstanding lugs 22 having holes at their outer ends to receive the adjusting rod 12^a. The screw threaded portion of the rod 12^a lies between the inner faces of lugs 22, and the rod is restrained from longitudinal movement but is free to be rotated at the will of the operator. Surrounding the threaded portion of the screw shank is a cooperating threaded sleeve 23 which may be split at one side and brought into engaging relation with the screw threads by means of a clamping bolt or screw as shown. This sleeve 23 forms the outer portion of a member 25 which is provided at its inner end with a tongue or fork 26 adapted to engage in the groove of the collar 18 secured to the shutter shaft 5. Rotation of the adjusting screw 12^a will thus effect longitudinal movement of member 25 through the medium of the screw threaded collar 23 and will consequently shift the shutter shaft 5 longitudinally in a direction depending upon the direction of rotation of the screw 12^a. To prevent the screw binding in the sleeve 23 a rod 27 is secured between lugs 28 and serves as a bearing upon which the member 25 is fitted to slide.

Longitudinal adjustment of the shutter

shaft 5 effects rotative adjustment of the shutter through the spiral gear 6 and pinion 7 in the manner already described.

In the particular machine above mentioned the supporting bracket 8 is secured to the frame of the apparatus by rotatively mounting it upon the bearing shutter driving shaft 4 and by providing at its upper edge a slot 28 adapted to fit over a pin or screw 29 to hold it into proper position. In packing the machine for shipment the shutter is removed from its shaft and the pin 29 loosened, after which it is possible to turn the bracket 8 about the shaft 4 as an axis so that the shutter shaft will lie close to the frame of the apparatus instead of projecting out beyond it as is the case when the parts are in operative position. In my present improvement the entire adjusting mechanism turns with the shutter bracket when the machine is packed and does not interfere in the least with the other parts of the machine.

In applying the form of device illustrated in Figs. 3, 4 and 5 to existing machines, a new shutter bracket with the shutter shaft and adjusting parts assembled thereon can be quickly substituted for the shutter bracket and attached parts already on the machine. This feature is desirable in that it facilitates shipment and minimizes the danger of breakage due to projecting parts being bent or broken.

It is also to be understood that my proposed shutter adjusting device may be otherwise modified in its details without departing from the spirit of the invention or the scope of the appended claims.

I claim:

1. In a picture projector comprising driving mechanism and a shutter actuated therefrom, a detachable bracket mounted on said projector, and means carried by said bracket for shifting the shutter shaft longitudinally to thereby alter the driving relation of certain of the shutter driving member and thus rotatively adjust said shutter relative to the driving mechanism.

2. In a picture projector comprising driving mechanism, a bracket secured to the frame of said projector, a rotating shutter supported by said bracket, connections between the shutter and driving mechanism, and means carried by said bracket for bodily shifting the shutter driving shaft to thereby rotatively adjust the shutter relative to the driving mechanism thru the medium of the gearing of said mechanism.

3. In a picture projector having a projector aperture, a rotating shutter having a shaft, driving mechanism therefor, and means for rotatively adjusting said shutter

relative to its driving mechanism, said means comprising a thumb screw at the exterior of the projector and connections between said thumb screw and the shutter shaft to effect bodily movement of the shaft.

4. In a picture projector, a bracket at the exterior of the projector, a shutter having a shaft rotatively mounted in said bracket, driving mechanism for said shaft, and means for adjusting said shutter relative to the driving mechanism, said means comprising a thumb screw carried by said bracket, a collar secured to the shutter shaft, and a member connecting said thumb screw with the shaft to thereby provide for shifting said shaft longitudinally and effecting a relative displacement of certain of the shutter driving elements.

5. In a picture projector, a bracket at the exterior of the projector, a shutter having a shaft rotatively mounted in said bracket, a spiral pinion on said shaft, a spiral driving gear cooperating with said pinion, and means carried by said bracket for effecting a longitudinal movement of said shaft and pinion, thereby affording a rotative adjustment of said shutter relative to the driving gear.

6. In a picture projector, a bracket at the exterior of the projector, a shutter having a shaft rotatively mounted in said bracket, a spiral pinion on said shaft, a spiral driving gear cooperating with said pinion, a thumb screw mounted in said bracket, and a member movable parallel to the axis of the thumb screw and actuated thereby for transforming rotative motion of the screw into longitudinal movement of the shutter shaft.

7. In a picture projector, a bracket at the exterior of the projector, a shutter having a shaft rotatively mounted in said bracket, a spiral pinion on said shaft, a spiral driving gear cooperating with said pinion, a thumb screw mounted in said bracket, a collar provided on the shutter shaft, and a reciprocating member engaging said collar and said thumb screw for transforming rotative motion of the screw into longitudinal movement of the shutter shaft.

8. In a picture projector, a bracket at the exterior of the projector, a shutter having a shaft rotatively mounted in said bracket, a spiral pinion on said shaft, a spiral driving gear cooperating with said pinion, a thumb screw mounted in said bracket, a collar provided on the shutter shaft, a bearing rod in parallelism with said shaft, and a member slidable on said rod adapted to transform rotative motion of the screw into longitudinal movement of the shutter shaft.

In testimony whereof I affix my signature.

WILLIAM ELLWOOD.
